Application February 9, 1954, Serial No. 28,931

Term of patent 7 years

(Cl. D92—1)

To all whom it may concern:

Be it known that I, Marion R. Hamre, a citizen of the United States, residing in the city of Oceanside, county of Nassau and State of New York, have invented a new, original, and ornamental Design for a Textile Fabric or Similar Article, of which the following is a specification, reference being had to the accompanying drawing, forming a part thereof.

The figure of the drawing is a plan view of a textile fabric showing my new design.

The dotted lines outline a design unit which unit is repeated over the fabric in regular succession as indicated by the extensions beyond the unit boundaries.

I claim:

The ornamental design for a textile fabric or similar article, as shown and described.
